UNITED STATES PATENT OFFICE.

JAMES T. COWLEY, OF LOWELL, MASSACHUSETTS, ASSIGNOR TO THE LAMSON CONSOLIDATED STORE SERVICE COMPANY, OF NEWARK, NEW JERSEY.

CABLE CARRIER.

SPECIFICATION forming part of Letters Patent No. 608,954, dated August 9, 1898.

Application filed August 20, 1896. Renewed July 12, 1898. Serial No. 685,768. (No model.)

To all whom it may concern:

Be it known that I, JAMES T. COWLEY, of Lowell, county of Middlesex, and State of Massachusetts, have invented a certain new and useful Improvement in Cable Carriers, of which the following is a full, clear, and exact description of the invention, which will enable others skilled in the art to which it appertains to make and use the same.

10 My invention relates to improvements in cable carriers; and it has for its object to provide means at each station for removing the last carrier arriving at the station without removing the other carriers that may be in said station. This and other objects are carried out by the apparatus hereinafter described.

My invention consists of certain novel features hereinafter described, and particularly pointed out in the claims.

20 In the accompanying drawings, which illustrate a construction embodying my invention, Figure 1 is a perspective view of one of the stations of a cable carrier apparatus and represents the last station on the line. Fig. 2 is an end view of the station, taken in the direction indicated by the arrow, Fig. 1. Fig. 3 is an enlarged detail view of the lower portion of the bracket shown in Fig. 2. Fig. 4 is an enlarged detail side view, partly in 25 section, of the bracket and other coöperating parts shown in Fig. 2. Fig. 5 is an enlarged detail view, the same as Fig. 4, but showing the carrier being removed. Fig. 6 is a top plan view of one of the carriers. Fig. 7 is a plan view of the bottom of the same. Fig. 8 is an end view of the carrier, showing the cable-gripping mechanism. Fig. 9 is a perspective view of the carrier, showing the gripping mechanism in engagement with the propelling-cable. Fig. 10 is a detail sectional view of one of the rollers on the carrier and described hereinafter. Fig. 11 is a perspective view looking from below and illustrating the position of a carrier passing from the 35 main track onto the branch track.

Like letters of reference refer to like parts throughout the several views.

Referring now to Fig. 1, in which there is illustrated the last station on the line of a cable carrier apparatus, the track A, composed of the rails A', represents the forwarding-track.

A² represents an opening formed by bending the forwarding-rails A' to permit the carrier D being placed upon the track A to engage with the propelling-cable C and to be forwarded along the track A.

B represents the return-track, composed of the opposite rails B', on which the carriers are returned to their respective stations along the line. The rails A' of the forwarding-track and the rails B' of the return-track are secured to and supported by the brackets E and E' at E².

B³ represents a branch track composed of opposite rails B³. These rails are curved 65 downwardly, as shown in Figs. 1 and 2, and are secured to the bracket E' at E³.

B⁴ is a short section of track located at each station and composed of the opposite rails B⁵ and arranged to form a continuation of the 70 branch track B³. These rails B⁵ are supported at E⁵ on the bracket E at one end, and the opposite ends are secured to the brackets G at G'. The brackets E and E' are suspended by the wires E⁶.

75 D represents one of the carriers and is fully illustrated in Figs. 6 to 10, inclusive, in which D' represents the cover, held in a closed position by a suitable spring-catch, which is adapted to be operated by a push-button to 80 release the cover D', and the spring D⁸ will throw up the cover and open the interior of the carrier.

D⁴ represents suitable guides by which the carriers are switched at their respective stations. As shown, these guides are arranged to enter the last station on the line, and by locating these guides in a different position on the cover D' of the carrier D the carrier can be made to switch at any desired station by arranging the switches at said station to correspond with the location of the guides D⁴ on the carrier D.

D⁶ represents a lever provided with a pin D⁶, upon which the gripping-jaws D⁷ are pivotally mounted, and said lever is journaled in suitable lugs on the rear side of the carrier. These jaws are each provided with a cam-slot D⁸, which works upon the stud D⁹, secured to the end of the carrier, and the 90 cam-slots D⁸ are of such form that the jaws will be open as the lever D⁶ is lowered in po-

sition to engage with the propelling-cable C, as shown in dotted lines, Fig. 9. When the lever D⁵ is released, the spring D¹⁰, located at the back of the carrier and around the lever D⁵, will operate to raise the lever D⁵ and close the jaws D⁷ upon the propelling-cable C, as shown in Fig. 9.

D¹¹ is a plate secured to the bottom of the carrier by the screws D¹². This plate is provided with ears D¹³, which are adapted to pass under the rails A' of the track A and hold the carrier thereon.

D¹⁴ represent friction-rollers mounted upon the screws D¹² and free to revolve thereon. The object of these rollers is to reduce the friction caused by the carrier traveling along the track and passing around the corners and into the stations. Over each of these rollers D¹⁴ and the plate D¹¹ is placed a flat spring D¹⁵, slightly curved, as shown in Fig. 10. The object of these springs is to prevent the rollers D¹⁴ from rattling, due to wear and other causes, as the carrier travels along the track.

The carrier D belonging to the last station, as shown in Fig. 1, having been placed upon the forwarding-track A at the opening A² and the lever D⁵ having been depressed by the operator, the lower ends of the jaws D⁷ will engage with the propelling-cable C and be carried to the cashier and will be returned by him over the return-track B. As the carrier approaches the station to which it belongs it will be guided and steadied by the guides E⁴, secured on the bracket E, and passing said guides the guide-pins D⁴ on the carrier D will pass along the slat F⁵ on the station and engage with the switch-slat F¹⁰, when the carrier will be moved away from the return-track B and onto the branch track B², and on passing onto said branch track the lever D⁵ of the carrier D will pass under the disengaging cam F¹¹, secured to the lug F¹² on the bracket F (see Fig. 11) and will be depressed and disengage the carrier from the propelling-cable C, which will return to its normal position between the rails B' B' of the track B, as indicated in Fig. 11 in dotted lines. The carrier being thus disengaged will travel by its momentum around the curved portion of the track B² and onto the track-section B⁴.

The slats F⁴ and F⁵ are supported at one end upon the bracket E by the pin F⁹, located in the groove F⁷ of the lug F⁶, and said pin F⁹ passes through holes in the ends of the slats F⁴ and F⁵, which are located in the vertical slots F⁸. The opposite ends of these slats and the lower switch-slat F¹⁰ are supported in a similar manner in the bracket F. In the lower portion of this bracket F the rods B' and B⁸ are secured at F² and F³, respectively. E⁷ represents a bracket for assisting in supporting the rails A' A' of the forwarding-track A.

Usually at each station there are three or four carriers by which cash is forwarded by

the salesman to the cashier, and after the change is made the carrier is returned by the cashier to the salesman and, being switched onto the branch track, comes in rear of the carriers which, unless the day is a very busy one, have not been used. Now in order to obtain this last carrier and return the change to the purchaser the operator takes hold of the carrier and by pulling down on the same, the pins G³ and G⁴ working in the slots G⁵ and G⁶, respectively, (see Figs. 4 and 5,) in the bracket E', one end of the track-section B⁴ will be pulled down against the tension of the spring G⁷, one end of which is attached to the pin G⁸, and the opposite end of said spring G⁷ is secured to the bracket E' at G⁸ and assumes the position shown in full lines, Fig. 5, when the carrier may be moved off from the end of the track-section B⁴, the guides D¹³ on the carrier passing below the rails B³, as shown in Figs. 3 and 7. After the carrier is removed the spring G⁷ will act to return the end of the track-section B⁴ to its normal position in alinement with the branch track B² in position to receive the carriers which may be switched.

From the above it is clear that the desired carrier can be removed by the salesman without disturbing the other carriers, whereas in the old apparatuses previously used it was necessary to slide off all of the carriers in front of the desired carrier in order to remove it.

I do not limit myself to the arrangement and construction shown, as the same may be varied without departing from the spirit of my invention.

Having thus ascertained the nature of my invention and set forth a construction embodying the same, what I claim as new, and desire to secure by Letters Patent of the United States, is—

1. In a cable carrier, a forwarding-track, a return-track, a branch track adapted to receive carriers switched from the return-track, and a track-section normally in alinement with said branch track and adapted to receive the diverted carriers and having its end nearest the branch track adapted to be moved from said alinement to permit the removal of carriers therefrom.

2. In a cable carrier, a forwarding-track, a return-track, a branch track adapted to receive carriers switched from the return-track, a track-section normally in alinement with said branch track and adapted to receive the diverted carriers and having its end nearest the branch track adapted to be moved from said alinement to permit the removal of carriers therefrom, and means for returning said track-section to its normal position.

3. In a cable carrier, a forwarding-track, a return-track, a branch track adapted to receive carriers switched from the return-track, a track-section normally in alinement with said branch track and adapted to receive the diverted carriers and having its end nearest

the branch track adapted to be moved from said alinement to permit the removal of carriers therefrom, and a spring connected to said track-section for returning it to its normal position.

4. In a cable carrier, a track composed of opposite rails, a carrier adapted to travel on said track and provided with a plate secured to the bottom of the carrier for holding said carrier on said track, and rollers located between the bottom of the carrier and the said plate to bear against said rails in the travel of the carrier.

5. In a cable carrier, a track composed of opposite rails, a carrier adapted to travel on

said track and provided with a plate secured to the bottom of the carrier for holding said carrier on said track, rollers located between the bottom of the carrier and the said plate to bear against said rails in the travel of the carrier, and a spring bearing on said rollers for the purpose set forth.

In testimony whereof I have signed my name to this specification, in the presence of two subscribing witnesses, on this 1st day of 25 August, 1896.

JAMES T. COWLEY.
